UNITED STATES PATENT OFFICE.

FRANK HIEMENZ, OF ST. LOUIS, MISSOURI.

DESIGN FOR A CLOTHES-RACK FRAME.

SPECIFICATION forming part of Design No. 30,120, dated January 31, 1899.

Application filed January 3, 1899. Serial No. 701,049. Term of patent 14 years.

To all whom it may concern:

Be it known that I, FRANK HIEMENZ, a citizen of the United States, residing in the city of St. Louis, State of Missouri, have invented and produced a new and original Design for a Clothes-Rack Frame, of which the following is a specification.

Figure 1 is a front elevation of a clothes-rack frame embodying my new design. Fig. 2 is a top plan view, and Fig. 3 is a side elevation.

The leading or essential feature consists of the vertical back portion 4; the portions 5 and 6, extending in horizontal alinement from opposite sides and near the center of said back portion; the portion 7, running along the front face of the back portion from near the upper end to near its lower end; the portion 8, extending from the upper end of the por-

tion 7 forwardly and downwardly and then 20 backwardly and downwardly to the lower end of said portion 7; the portion 9, connecting the center of the portion 8 with the outer end of the portion 5; the portion 10, connecting the center of the portion 8 with the outer end 25 of the portion 6, said portions 9 and 10 forming a semicircle in plan; and the portions 11, extending forwardly from the upper edge of the portions 5 and 6, extending across and in front of the portions 4 and 7. 30

I claim—

The design for clothes-rack frame, substantially as herein shown and described.

FRANK HIEMENZ.
